UNITED STATES PATENT OFFICE.

AARON S. KATZ, OF NEW YORK, N. Y.

DESIGN FOR A CONSOLE TABLE AND CABINET.

Application filed January 13, 1928. Serial No. 24,865. Term of patent 3½ years.

To all whom it may concern:

Be it known that I, AARON S. KATZ, a citizen of the United States, residing at the borough of Bronx, in the city and State of New York, county of Bronx, have invented a new, original, and ornamental Design for a Console Table and Cabinet, of which the following is a specification, reference being had to the accompanying drawing, forming part thereof.

The figure is a perspective view of a console table and cabinet showing my new design.

I claim:

The ornamental design for a console table and cabinet as shown.

AARON S. KATZ.
